FIREARM AND ROTARY MAGAZINE THEREFOR
 John L. Boudreau, 655 Short Beach Road,
 Stratford, Conn.
 Filed Jan. 24, 1962, Ser. No. 168,412
 20 Claims. (Cl. 42—19)

This invention relates to handheld firearms and particularly to a novel rotary magazine for supplying a plurality of cartridges to said firearm.

It is an object of the present invention to provide a firearm having a readily removable or releasable rotary magazine thereon which can be released in the event of undue pressure, to vent the firearm.

Another object of the invention is to provide a novel magazine construction which is simple and efficient in operation and which can be readily manufactured and assembled.

In carrying out these objects the present invention provides a novel magazine construction which is adapted to be mounted on a firearm, preferably in a recess formed in the firearm, which magazine includes a housing preferably having an outer surface to conform or blend into the outer contour of the firearm. The magazine is held in position by a yieldable detent which can permit the magazine to be quickly inserted and replaced with a minimum of effort. The construction also provides a safety feature in that it will yield under undue pressures in the firearm and vent the firearm to relieve the pressures.

The magazine of the present invention is simple in construction and comprises a rotary carrier mounted in a bore in the housing and provided on its surface with longitudinally extending recesses for supporting and retaining cartridges for solely rotation therewith whereby jamming due to sliding action of the cartridges in the magazine is eliminated. The housing which encloses the carrier is preferably provided with a single longitudinally extending opening which faces the firearm, when the magazine is in position thereon, and has guide means adjacent the opening for supporting a cartridge in a ready position in which it can be delivered to the firing chamber of the firearm.

A feature of the invention resides in the fact that the guide means is preferably in the form of longitudinal ribs located on each side of the opening and has a space therebetween for receiving the cartridge from the carrier and has means for holding the cartridge against lateral movement therefrom so that the magazine can be pre-loaded. The ribs, however, are provided with means whereby the cartridge can be released therefrom by longitudinal movement of the cartridge therealong as it is fed to the firing chamber.

The carrier is normally urged to rotate in a direction in which the cartridges are fed from the recesses to the opening. Adjacent the opening there is provided deflecting means which move the cartridges laterally out of the recesses and into the space between the guide ribs. If desired, the trailing edges of the recesses can be curved or shaped to provide a camming action to assist the deflector means to move the cartridge into the guide means.

In order to move the last cartridge into the ready position, the carrier has a pusher which is mounted thereon for controlled relative movement with respect to the carrier so as to push the last cartridge into ready position in response to turning movement of the carrier. Control means is provided on the magazine for controlling the rotation of the carrier to slightly more than one revolution, the slight excess being sufficient to cause the pusher to move the last cartridge into ready position.

Further, the means for limiting the rotation of the carrier may include a manually operable means whereby the carrier can be rotated against the urging means to

2

facilitate the insertion of the cartridges into the magazine during the loading operation.

Another feature of the invention resides in the fact that the magazine may accommodate rim-type cartridges by being provided with a counterbore adjacent the end of the carrier into which the rims may pass so that the cartridge lies flat in the carrier and can be readily controlled in its rotary movement with the carrier.

A still further feature of the present invention resides in the simplicity of the construction of the magazine which enables it to be readily manufactured and assembled at a relatively low cost.

Other features and advantages of the invention will be apparent from the specification and claims when considered in connection with the accompanying drawings in which:

FIGURE 1 shows a side view of a pistol with the magazine in place.

FIG. 2 is a longitudinal sectional view of the pistol taken through the magazine and adjacent pistol structure.

FIG. 3 is a section taken along line 3—3 of FIG. 2.

FIG. 4 is a side view of the magazine.

FIG. 5 is an end view of the magazine looking from the right in FIG. 2.

FIG. 6 is a view similar to FIG. 2 showing the cartridges in position.

FIG. 7 is a sectional view similar to FIG. 3 showing the cartridge and pusher in position.

FIG. 8 is a bottom view of the magazine.

The rotary magazine of the present invention has particular use in handheld firearms such as pistols and rifles to supply a plurality of cartridges thereto and can be mounted thereon in various locations as may be practical and convenient.

In the herein illustrated form of the invention a magazine 10 is inserted in a recess 11 provided in the frame 12 of a 22 caliber pistol of the type disclosed in my Patent No. 2,899,767 having a barrel 13 disposed in a lower position on the frame. The magazine, which is positioned above the barrel of the pistol, is designed to supply a large number of cartridges thereto. As shown in FIG. 2, the recess 11 opens into a transfer chamber 12a within the frame of the pistol adjacent the firing chamber 14 formed in the barrel 13 which is closed by a sliding breechblock 15 which carries the usual extractor and ejector members, not shown.

In accordance with the preferred form of the invention, the magazine comprises a housing 16 having a cartridge carrier 17 rotatably mounted therein. The magazine is held in the recess by a detent means herein illustrated as a spring-pressed ball 18 carried by the frame 12 of the pistol and engaging an aperture or recess 19 in the end of the magazine. This permits the magazine to be readily inserted and removed from the pistol and also provides a safety factor in that it permits the magazine to move outwardly upon building up of abnormal pressure in the transfer area, whereby said area is vented to reduce the pressure.

While the magazine may take various shapes, it is preferred to have the housing shaped or contoured to blend with the surface of the firearm adjacent the recess. In the herein illustrated form of the invention the housing has a curved outer surface which, as shown in FIGS. 1 and 2, blends into the contour of the firearm to provide a construction which is balanced, can be readily handled without the magazine interfering with its use, and without interference in the sighting of the pistol by the sights S₁ and S₂.

The housing as herein illustrated comprises a cylindrical member 20 forming side walls and a pair of end walls 21, 22. The housing is provided with a longitudinal bore 23 therein. While the housing may be fabricated in many

ways, it is at present preferred to form the end wall 21 integral with the side walls 20 to provide a casing and to form the end wall 22 as a separate member to be inserted into position to close the casing and be pinned in place to facilitate the assembly as will be explained.

The end walls 21, 22 are provided with aligned apertures 24, 25 which form bearings for rotatably mounting a shaft 26 secured to the carrier 17. One end 26a of the shaft 26 projects beyond the end wall 21 and the other end of the shaft is carried by the aperture 25 in a sleeve 27 forming a continuation of the aperture 19 in the end wall 22 so that the carrier is mounted coaxially with the bore in the housing as shown in FIGS. 2 and 3.

On the surface of the carrier are a plurality of longitudinally extending cartridge-receiving recesses 28, herein illustrated as being ten in number. The recesses are so spaced with respect to the wall 20 of the bore 23 of the housing that cartridges 29 received in the recesses will be retained therein for solely rotating movement with the carrier by said wall.

If it is desired to have the magazine accommodate cartridges having rims 29a, the bore of the housing can be counterbored at 23a adjacent the end of the carrier to permit the rims to ride therein while the cartridge is supported in the recess.

In accordance with the preferred form of the invention, the housing has a single elongate opening 30 in the side wall through which the cartridges pass into and out of the magazine. This opening, as shown in FIGS. 2 and 3, is in that portion of the side wall adapted to face the firearm so that the magazine is completely closed to foreign matter when in position on the firearm.

As herein illustrated, guide means is provided on the magazine for guiding the cartridges laterally from the carrier into a ready position in which the sliding breechblock 15, as it moves to close the firing chamber 14, will move the cartridge into the firing chamber.

While the guide means may take many forms, in the herein illustrated form of the invention it comprises a pair of ribs 31, 32 each located on a side of the opening to project therefrom and receive the cartridges therebetween as they are fed from the carrier. The carrier is normally urged to rotate in the direction of the arrow A in FIGS. 3 and 7 to deliver the cartridges carried thereby seriatim to the guide means. While this rotating means may take many forms, in the illustrated form of the invention this means comprises a helical spring 33 having one end 33a secured to the carrier and the other end 33b secured to the removable end plate 22. Preferably, the spring surrounds the sleeve 27 and an aligned boss 34 on the carrier and is supported thereby.

In order to deflect the cartridges from the recesses into the space between the ribs in response to the rotation of the carrier, the present invention provides an annular groove 35 in the surface of the carrier intermediate the ends of the recesses and provides a deflecting finger 36 on the housing at the far edge of the opening 30 projecting into the groove so that as the cartridges are moved by the carrier into a position overlying the opening the deflecting finger will cause them to move laterally and into the opening and into said space between the ribs. To facilitate this lateral movement, the trailing edge 28a of each of the recesses is curved or shaped as shown in FIG. 3 to cooperate with the cartridge engaging the deflecting member in a manner that continued rotation of the carrier will cause the cartridge to be moved laterally away from the carrier and out of the recess. As herein illustrated in FIG. 7, as the first cartridge is moved laterally, the carrier will move the next cartridge into position behind the first cartridge and push said first cartridge into the space between the ribs at the rear end thereof. The ribs, adjacent the rear end thereof, are provided with lips 40 which engage the cartridge and hold it against further lateral movement and in a ready position in which the lower edge of the cartridge is disposed to be engaged

by the sliding breechblock 15. It will be supported on the breechblock as shown in FIG. 6 and when the breechblock moves rearwardly to withdraw and eject the spent cartridge casing, the rim will drop to a position to be engaged by the breechblock and fed forwardly toward the firing chamber. The cartridges so held by the guide means will prevent further rotation of the carrier under the urging of the spring until the first cartridge has been moved from ready position. When this is accomplished, the carrier 17 again rotates to feed the next cartridge to the opening.

In order to move the last cartridge in the magazine to ready position, the magazine of the present invention is provided with a pusher member 41 which is carried by a wire bail 42 pivotally mounted on the carrier for relative movement with respect to the carrier. The pusher member lies in the last recess on the carrier and when the carrier has fed the last cartridge into the opening, continued rotation of the carrier will cause the pusher member to move into the opening as shown in FIG. 3 so as to apply pressure to the last cartridge and maintain it in the ready position in the guide means. Preferably the pusher has a conical end 41a which will cause it to retract in the event that it is inadvertently engaged by the sliding breech-block.

In order for the pusher to accomplish this, it will be seen that the carrier must rotate through slightly more than one revolution. In the herein illustrated form of the invention, the means for controlling the rotation of the carrier for slightly more than 360° comprises an arm 43 rotatably mounted on the end 26a of the shaft extending through the end wall 21. The arm 43 has a stop pin 44 passing through the arm so as to have ends 44a, 44b projecting from the faces of the arm. The end 44a of the stop pin cooperates with a slot 45 in the end plate 21 and limits the movement of the arm to a relatively small arc. A stop arm 46 is fixed to the end 26a of the shaft and projects outwardly to engage the other end 44b of the stop pin so that the rotation of the shaft 26 will be limited, under the action of the spring, to a complete revolution of the shaft plus the amount of rotation permitted by the slot 45 in the end disk through its cooperation with the arm 43 and stop pin 44.

The cartridge in the guide means is adapted to be moved longitudinally of the ribs by the sliding breechblock and fed to the firing chamber. The forward ends of the ribs 31, 32, as shown in FIGS. 6 to 8, are devoid of the lips 40 so that the cartridge, as it moves longitudinally of the ribs, is freed from any retaining action of the lips and can be released from the magazine. Preferably, the forward ends of the rib members are provided with downwardly deflecting cams 47, 48 for guiding the nose and rim of the cartridge downwardly, as shown in the dot and dash lines in FIG. 7, into position to move into the firing chamber of the pistol.

The stop arm 46 can also function as the means for rotating the carrier 17 in a reverse direction against the action of the helical spring when it is desired to load the magazine. In this case, with the magazine released from the pistol, cartridges are fed longitudinally of the guide ribs into position in which they overlie the opening in the housing. The cartridges are then fed through the opening, the first cartridge lying in the recess adjacent the pusher. The carrier is then rotated against the action of the spring by the arm 46 to bring the next recess in line with the opening and the next cartridge is deposited in the recess. This continues until all of the recesses, except the one carrying the pusher, are filled with cartridges and the last cartridge is then inserted into ready position in the ribs and will be held in this position by the lips and the pressure of the cartridge at the opening. Thus, the magazine will hold ten cartridges. Since the magazines can be preloaded, one may have a supply of magazines on hand and quickly and easily interchange them with the pistol to provide for a rapid fire operation of the pistol.

The magazine of the present invention is simple to construct and easy to assemble. As shown in the drawings, the cylindrical member 20 forming the side walls and the end wall 21 are formed integral. The ribs 31, 32 are secured to the cylindrical member to project therefrom and form a casing unit. The shaft 26 which has the arm 43 and stop arm 46 mounted thereon is inserted through the aperture 24 in the wall 21. The carrier 17 is positioned on the shaft and is pinned thereto by pin 49. The torsion spring is put in position and has one end secured to the carrier and the other end secured to the end plate 22, and end 26b of the shaft is inserted in the bearing aperture in sleeve 27 on the end plate 22. The end plate is rotated sufficiently to tension the torsion spring and is then inserted into the end of the casing and pinned in position by pin 50 or any suitable securing means, completing the magazine assembly.

Thus, it will be apparent that the elements which can be readily machined or otherwise formed and assembled will very economically produce magazines for use with firearms.

Further, it will be noted that inasmuch as the movement of the cartridge in the magazine is solely a rotary movement and there is no longitudinal sliding movement as might wipe off wax from the cartridges or lead from the usual lead nose of the cartridge that the building up, particularly in cold weather, of obstacles to the movement of the cartridge is substantially eliminated, and a smooth-working, effective cartridge supply is provided for the firearm.

Variations and modifications may be made within the scope of the claims and portions of the improvements may be used without others.

I claim:

1. In a handheld firearm having a firing chamber and a magazine receiving recess adjacent the firing chamber, the combination of a rotatable multiple cartridge magazine mounted in the recess, detent means for holding the magazine in the recess, said magazine comprising a housing having an outer surface shaped to blend with the outer surface of the firearm adjacent the recess and a longitudinal bore, a carrier carried by a shaft mounted coaxially in the bore for rotation therein and having a plurality of longitudinally extending recesses in the surface thereof for receiving and holding a plurality of cartridges therein for solely rotary movement with the carrier; a longitudinally extending opening in the side of the housing facing the firing chamber in the firearm; rigid guide means projecting from the housing on each side of the opening; and means urging said carrier in a direction to deliver cartridges through said opening and into said guide means, said guide means having means for retaining the cartridge against lateral movement in a ready position to be moved longitudinally of the guide means, said guide means having means for releasing the cartridge therefrom incident to said longitudinal movement whereby the cartridge may be inserted into the firing chamber.

2. The invention as defined in claim 1 wherein said detent means comprises a spring-pressed ball cooperating with a recess at the end of the housing.

3. In a handheld firearm having a firing chamber, a magazine receiving recess adjacent the firing chamber, and moving means for moving cartridges from a ready position to the firing chamber, the combination of a removable multiple cartridge magazine mounted in said recess and comprising a housing having a bore provided with substantially cylindrical walls; a substantially cylindrical carrier mounted on a shaft disposed coaxially in the bore for rotation therein and having a plurality of longitudinally extending recesses in the surface thereof and spaced from the walls of the bore for receiving and holding a plurality of cartridges therein for solely rotary movement with the carrier; a longitudinally extending opening in the side of the housing facing the firing chamber in the firearm; fixed rigid guide ribs projecting from

the housing on each side of the opening; and means urging said carrier in a direction to deliver cartridges through said opening and into the space between said guide ribs, said guide ribs having means for retaining the cartridge against lateral movement in said ready position to be engaged by the moving means to be moved thereby longitudinally of the guide ribs, said guide ribs having means for releasing the cartridge therefrom incident to said longitudinal movement whereby said cartridge may be fed into said firing chamber.

4. In a handheld firearm having a firing chamber, a transfer area adjacent the firing chamber, a slideable breechblock movable in the transfer area, and a magazine receiving recess opening into said transfer area, the combination of a removable multiple cartridge magazine mounted in said recess and comprising a housing having a bore provided with substantially cylindrical walls, a substantially cylindrical carrier carried by a shaft mounted coaxially in the bore for rotation therein and having a plurality of longitudinally extending recesses in the surface thereof and spaced from the walls of the bore for receiving and holding a plurality of cartridges therein for solely rotary movement with the carrier; a longitudinally extending opening in the side of the housing facing the transfer area; rigid guide ribs projecting from the housing on each side of the opening to extend into the transfer area; and urging means rotating said carrier in a direction to deliver cartridges through said opening and into the space between said guide ribs, said guide ribs having means for retaining the cartridge in a ready position in the transfer area to be engaged by the slideable breechblock and moved thereby longitudinally of the guide ribs toward the firing chamber, said guide ribs having means for releasing the cartridge therefrom incident to said longitudinal movement.

5. In a handheld firearm having a firing chamber, a transfer area adjacent the firing chamber, and a slideable breechblock movable in the transfer area, the combination of a removable multiple cartridge magazine mounted thereon to supply cartridges to said transfer area comprising a housing having a bore provided with substantially cylindrical walls; a substantially cylindrical carrier carried by a shaft mounted coaxially in the bore for rotation therein and having a plurality of longitudinally extending recesses in the surface thereof and spaced from the walls of the bore for receiving and holding a plurality of cartridges therein for solely rotary movement with the carrier; a longitudinally extending opening in the side of the housing; rigid ribs projecting from the housing on each side of the opening and adapted to extend into the transfer area; means urging said carrier in a direction to deliver cartridges to said opening; and means at said opening for deflecting the cartridge from the recess laterally into the space between said guide ribs, said guide ribs having means for retaining the cartridge against lateral movement in a ready position in the transfer area to be engaged by the slideable breechblock and moved thereby longitudinally of the guide ribs toward the firing chamber, said guide ribs having means for releasing the cartridge therefrom incident to said longitudinal movement.

6. A removable multiple cartridge magazine to be inserted in a recess in a handheld firearm having a transfer area disposed between the recess and a firing chamber, and moving means for moving a cartridge from the transfer area to the chamber comprising a housing having an outer contour adapted to blend with the contour of the firearm adjacent the recess and a bore provided with substantially cylindrical walls, a longitudinally extending opening in the side of the housing, and rigid guide ribs projecting from the housing on each side of the opening and adapted to extend into the transfer area adjacent the firing chamber; a substantially cylindrical carrier carried by a shaft mounted coaxially in the bore for

rotation therein and having a plurality of recesses in the surface thereof for receiving and holding a plurality of cartridges therein for solely rotary movement with the carrier; means urging said carrier in a direction to deliver cartridges to said opening; and means at said opening for deflecting the cartridge from the recess laterally into said guide ribs, said guide ribs having means for normally retaining the cartridge therein and against lateral movement therefrom, said cartridge being held in a position adapted to be engaged by the moving means and moved thereby longitudinally of the ribs toward the firing chamber, said ribs having means thereon for releasing the cartridge therefrom and guiding the cartridge to the firing chamber incident to said longitudinal movement of the cartridge.

7. A removable multiple cartridge magazine adapted to be inserted into a recess in, and to supply cartridges to a handheld firearm comprising a housing provided with side walls and end walls, said housing having an outer configuration to blend with the contour of the firearm adjacent the recess and having a longitudinally disposed cylindrical bore, said end walls having aligned bearings; a substantially cylindrical carrier having a shaft mounted in said bearings coaxially of the bore for rotation therein, said carrier having a plurality of longitudinally extending recesses in the surface thereof and spaced from the walls of the bore for receiving and holding a plurality of cartridges therein for solely rotary movement with the carrier; a longitudinally extending opening in the side of the housing adapted to face the firing chamber in the firearm; rigid guide ribs projecting from the housing on each side of the opening and adapted to be moved into cooperative relation with said firearm; and torsion spring means urging said carrier to rotate in a direction to deliver cartridges through said opening into the space between said guide ribs, said guide ribs having inwardly extending lips adjacent the opening forming retaining means for retaining the laterally deflected cartridge in a ready position.

8. A removable multiple cartridge magazine adapted to be mounted on and to supply cartridges to a handheld firearm having a firing chamber comprising a housing having a bore provided with substantially cylindrical walls, a substantially cylindrical carrier carried by a shaft mounted coaxially in the bore for rotation therein, said carrier having a plurality of longitudinally extending recesses in the surface thereof and spaced from the walls of the bore for receiving and holding a plurality of cartridges therein for solely rotary movement with the carrier; a longitudinally extending opening in the side of the housing adapted to face the firing chamber in the firearm, and rigid guide ribs projecting from the housing on each side of the opening and adapted to be moved into cooperative relation with said firearm; urging means normally rotating said carrier in a direction to deliver cartridges through said opening into the space between said guide ribs, said guide ribs having retaining means for retaining the laterally deflected cartridge in ready position therebetween; and manual means connected to said carrier for rotating the same against the urging means to permit cartridges to be inserted through the opening into the recesses in the carrier to load the magazine.

9. A removable multiple cartridge magazine adapted to be mounted on and to supply cartridges to a handheld firearm having a firing chamber comprising a housing having a longitudinal bore, a carrier mounted coaxially in the bore for rotation therein, means for limiting rotation of the carrier to slightly more than one revolution, said carrier having a plurality of longitudinally extending recesses in the surface thereof for receiving and holding a plurality of cartridges therein for solely rotary movement with the carrier; a longitudinally extending opening in the side of the housing adapted to face the firing chamber in the firearm, and rigid guide ribs projecting from the housing on each side of the opening and adapted to

be moved into cooperative relation with said firearm; and means urging said carrier to rotate in a direction to deliver cartridges through said opening into the space between said guide ribs, said guide ribs having retaining means for retaining the laterally deflected cartridge in ready position therebetween.

10. A removable multiple cartridge magazine adapted to be mounted on and to supply cartridges to a handheld firearm comprising a housing provided with side walls and end walls, said housing having a longitudinally disposed cylindrical bore, the end walls having aligned bearings, a substantially cylindrical carrier having a shaft mounted in said bearings coaxially of the bore for rotation therein, said carrier having a plurality of longitudinally extending recesses in the surface thereof and spaced from the walls of the bore for receiving and holding a plurality of cartridges therein for solely rotary movement with the carrier; a longitudinally extending opening in the side of the housing adapted to face the firing chamber in the firearm, and guide ribs projecting from the housing on each side of the opening and adapted to be moved into cooperative relation with said firearm; torsion spring means in the housing urging said carrier to rotate in a direction to deliver cartridges through said opening into the space between said guide ribs, said guide ribs having inwardly extending lips adjacent the opening forming retaining means for retaining the laterally deflected cartridge in ready position in said guide ribs; and floating stop means carried by one end wall for limiting rotation of the carrier to slightly more than 360°.

11. A removable multiple cartridge magazine adapted to be mounted on and to supply cartridges to a handheld firearm comprising a housing provided with side walls and end walls, said housing having a longitudinal bore, the end walls having aligned bearings, a carrier having a shaft mounted in said bearings coaxially of the bore for rotation therein, said carrier having a plurality of longitudinally extending recesses in the surface thereof for receiving and holding a plurality of cartridges therein for solely rotary movement with the carrier; a longitudinally extending opening in the side of the housing adapted to face the firing chamber in the firearm, and guide means projecting from the housing adjacent the opening and adapted to be moved into cooperative relation with said firearm; torsion spring means in the housing urging said carrier to rotate in a direction to deliver cartridges through said opening to said guide means, said guide means having inwardly extending lips adjacent the opening forming retaining means for retaining the laterally deflected cartridge in ready position in said guide ribs; and floating stop means carried by one end wall for limiting rotation of the carrier to slightly more than 360°, said means comprising a member rotatable on the shaft of the carrier and having a portion cooperating with spaced stop means on the end wall for limiting the movement thereof and a second member secured to said shaft and cooperating with said first member to stop rotation of the shaft.

12. A removable multiple cartridge magazine adapted to be mounted on and to supply cartridges to a handheld firearm comprising a housing provided with side walls and end walls, said housing having a longitudinal bore, the end walls having aligned bearings, a carrier having a shaft mounted in said bearings coaxially of the bore for rotation therein, said carrier having a plurality of longitudinally extending recesses in the surface thereof for receiving and holding a plurality of cartridges therein for solely rotary movement with the carrier; a longitudinally extending opening in the side of the housing adapted to face the firing chamber in the firearm, and guide means projecting from the housing adjacent the opening and adapted to be moved into cooperative relation with said firearm; torsion spring means in the housing urging said carrier to rotate in a direction to deliver cartridges through said opening to said guide means, said guide means having inwardly

extending lips adjacent the opening forming retaining means for retaining the laterally deflected cartridge in ready position in said guide ribs; and floating stop means carried by one end wall for limiting rotation of the carrier to slightly more than 360° , said means comprising an arm rotatable on the shaft of the carrier and having a stop pin projecting therethrough with one end cooperating with an aperture in the end wall to limit the arc of movement of said arm and a second arm secured to said shaft and having a portion engaging the other end of said stop pin to limit rotation of the carrier to 360° plus the movement of the stop pin.

13. The invention as defined in claim 12 wherein said second arm comprises a manual actuator for turning the carrier against the urging of the spring to facilitate loading of the magazine.

14. A removable multiple cartridge magazine for supplying cartridges to a transfer area in a handheld firearm having a firing chamber adjacent said transfer area and moving means for moving the cartridge from the transfer area into the firing chamber comprising a housing having a longitudinal bore provided with substantially cylindrical walls, a longitudinally extending opening in the side of the housing, and rigid guide means projecting from the housing on each side of the opening and adapted to extend into the transfer area; a substantially cylindrical carrier carried by a shaft mounted coaxially in the bore for rotation therein and having a plurality of longitudinal recesses in the surface thereof, said carrier being spaced from the walls of the bore a distance to maintain a plurality of cartridges in all but the last of said recesses for solely rotary movement with the carrier; a pusher member disposed in the last recess and mounted on the carrier for limited relative movement; means normally urging said carrier to rotate in a direction to deliver cartridges to said opening; and means at said opening cooperating with said carrier for deflecting the cartridges and pusher member from the recess laterally into said guide means, said guide means having means for locating the leading cartridge in ready position adapted to be engaged by the moving means and adapted to be moved thereby from the guide means into the firing chamber, said cartridge in ready position preventing rotation of the carrier to deliver the next cartridge to said guide means and said pusher member moving the last cartridge into ready position.

15. A removable multiple cartridge magazine adapted to be mounted on and to supply cartridges to a handheld firearm having a firing chamber comprising a housing having a bore provided with substantially cylindrical walls, a substantially cylindrical carrier carried by a shaft mounted coaxially in the bore for rotation therein, said carrier having a plurality of recesses in the surface thereof and spaced from the walls of the bore for receiving and holding a plurality of cartridges in all but the last recess and having a pusher disposed in the last recess for solely rotary movement with the carrier; a longitudinally extending opening in the side of the housing adapted to face the firearm, and rigid guide ribs projecting from the housing on each side of the opening and adapted to be moved into cooperative relation with said firearm; and means urging said carrier to rotate in a direction to deliver cartridges through said opening into the space between said guide ribs, means for limiting rotation of the carrier to slightly more than 360° to enable the pusher to move the last cartridge into said space between the ribs, said guide ribs having retaining means for retaining the laterally deflected cartridges in ready position therebetween.

16. A removable multiple cartridge magazine adapted to be mounted on and to supply cartridges to a handheld firearm having a firing chamber comprising a housing having a bore; a carrier mounted coaxially in the bore for rotation therein and having a plurality of longitudinally extending recesses in the surface thereof for receiving

and holding a plurality of cartridges in all but the last recess for solely rotary movement with the carrier; a longitudinally extending opening in the side of the housing adapted to face the firearm; guide means projecting from the housing adjacent the opening and adapted to be inserted into cooperative relation with said firearm; means urging said carrier to rotate in a direction to deliver cartridges to said opening; and means at said opening for deflecting the cartridges seriatim from the recesses laterally into said guide means, said guide means having retaining means for retaining the laterally deflected cartridge in a ready position against further lateral movement under urging of the next deflected cartridge, a pusher member connected to the carrier and disposed in the last recess for pushing the last cartridge into ready position, said guide means having means adapted to release the cartridge upon longitudinal movement of the cartridge therein from said ready position whereby the cartridge can be fed to the firing chamber.

17. A removable multiple cartridge magazine adapted to be mounted on and to supply cartridges to a handheld firearm having a firing chamber comprising a housing having a bore; a carrier mounted coaxially in the bore for rotation therein and having a plurality of longitudinally extending recesses in the surface thereof for receiving and holding a plurality of cartridges in all but the last recess for solely rotary movement with the carrier; a longitudinally extending opening in the side of the housing adapted to face the firearm; guide means projecting from the housing adjacent the opening and adapted to be inserted into cooperative relation with said firearm; means urging said carrier to rotate in a direction to deliver cartridges to said opening; and means at said opening for deflecting the cartridges seriatim from the recesses laterally into said guide means, said guide means having retaining means for retaining the laterally deflected cartridge in a ready position against further lateral movement under urging of the next deflected cartridge, a cartridge type pusher connected by a pivoted bail to the carrier and disposed in the last recess for pushing the last cartridge into ready position, said guide means having means adapted to release the cartridge upon longitudinal movement of the cartridge therein from said ready position whereby the cartridge can be fed to the firing chamber.

18. A removable multiple cartridge magazine adapted to be inserted in a recess in a handheld firearm having a firing chamber, comprising a housing having a longitudinal bore and a longitudinally extending opening in the side of the housing adapted to face the firearm; guide means projecting from the housing adjacent the opening and adapted to extend into cooperative relation with the firearm; a carrier mounted coaxially in the bore for rotation therein and having a plurality of longitudinally extending recesses in the surface thereof for receiving and holding a plurality of cartridges therein for solely rotary movement with the carrier and having an annular surface groove intermediate the ends of said recesses; means normally rotating said carrier in a direction to deliver cartridges to said opening; and means located at said opening and disposed in the annular groove for deflecting the cartridge from the recess laterally into said guide means, said guide means having means for normally retaining the cartridge therein and against lateral movement therefrom, and having means thereon for releasing the cartridge therefrom and guiding the cartridge to the firing chamber incident to said longitudinal movement of the cartridge in said guiding means.

19. A removable multiple cartridge magazine adapted to be mounted on and to supply cartridges to a handheld firearm having a firing chamber comprising a housing having a bore provided with substantially cylindrical walls, a substantially cylindrical carrier mounted coaxially in the bore for rotation therein and having a plurality of longitudinally extending recesses in the surface thereof and spaced from the walls of the bore for receiving and

holding a plurality of cartridges in said recesses for solely rotary movement with the carrier; a longitudinally extending opening in the side of the housing adapted to face the firearm; guide ribs projecting from the housing on each side of the opening and adapted to be inserted into cooperative relation with said firearm; means normally urging said carrier to rotate in a direction to deliver cartridges to said opening; and means at said opening for deflecting the cartridges seriatim from the recesses laterally into the space between said guide ribs, said carrier having the trailing edges of the recesses curved to form camming surfaces to aid the deflecting means move the cartridge in response to the rotation of said carrier and said guide ribs having retaining means for retaining the laterally deflected cartridge in ready position against further lateral movement under urging of the next deflected cartridge and having means adapted to release the cartridge upon longitudinal movement of the cartridge along said guide ribs from ready position whereby the cartridge can be fed to the firing chamber, said cartridge in ready position preventing rotation of the carrier to deliver the next cartridge to said guide ribs.

20. A removable multiple cartridge magazine adapted to be mounted on and to supply cartridges having rims thereon to a handheld firearm having a firing chamber comprising a housing having a bore provided with substantially cylindrical walls, a substantially cylindrical carrier mounted coaxially in the bore for rotation therein and having a plurality of longitudinally extending re-

cesses in the surface thereof and spaced from the walls of the bore for receiving and holding a plurality of cartridges therein for solely rotary movement with the carrier, said housing having a counterbore adjacent the end of the carrier to receive the rim of the cartridge whereby the cartridges are supported parallel to the axis of the carrier; a longitudinally extending opening in the side of the housing adapted to face the firearm, and rigid guide ribs projecting from the housing on each side of the opening and adapted to be moved into cooperative relation with said firearm; means urging said carrier in a direction to deliver cartridges to said opening; and means at said opening for deflecting the cartridges from the recess laterally into the space between said guide ribs, said guide ribs having retaining means for retaining the laterally deflected cartridge in ready position against further lateral movement and having means adapted to release the cartridge upon longitudinal movement of the cartridge along said guide ribs from ready position whereby the cartridge can be fed to the firing chamber.

UNITED STATES PATENT OFFICE
CERTIFICATE OF CORRECTION

Patent No. 3,133,369

May 19, 1964

John L. Boudreau

It is hereby certified that error appears in the above numbered patent requiring correction and that the said Letters Patent should read as corrected below.

Column 6, line 13, for "beechblock" read -- breechblock --; line 40, for "removeable" read -- removable --; line 50, after "rigid" insert -- guide --; line 63, after "magazine" insert -- adapted --; same column 6, line 67, after "the" insert -- firing --.

Signed and sealed this 13th day of October 1964.
